(57) **CLAIM**

We claim the ornamental design for an autonomous vehicle, as shown and described.

DESCRIPTION

FIG. 1 is a perspective view of an autonomous vehicle showing our new, original, and ornamental design;

FIG. 2 is a top view of the autonomous vehicle of FIG. 1; FIG. 3 is a side view of the autonomous vehicle of FIG. 1; FIG. 4 is an end view of the autonomous vehicle of FIG. 1; and,

FIG. 5 is a perspective view of the autonomous vehicle of FIG. 1 in a second example configuration.

The broken lines show portions of the autonomous vehicle that form no part of the claimed design.
